UNITED STATES PATENT OFFICE

157,332

BOTTLE CAP

George L. Bolard, Meadville, Pa.

Application February 26, 1947, Serial No. 137,182

Term of patent 7 years

(Cl. D58—10)

To all whom it may concern:

Be it known that I, George L. Bolard, a citizen of the United States, residing at Meadville, in the county of Crawford, and State of Pennsylvania, have invented a new, original, and ornamental Design for Bottle Caps, of which the following is a specification, reference being had to the accompanying drawing, forming a part thereof.

In the drawing:

Fig. 1 is a top view of a bottle cap, showing my new design;

Fig. 2 is an elevational view thereof;

Fig. 3 is a perspective view of the bottle cap shown in Fig. 2; and

Fig. 4 is a bottom view of the bottle cap shown in Figs. 2 and 3.

I claim:

The ornamental design for a bottle cap, substantially as shown.

GEORGE L. BOLARD.
